UNITED STATES PATENT OFFICE

104,192

DESIGN FOR A PORTABLE SERVICE BAR

Joseph J. Kopacka, Greensburg, Pa.

Application February 19, 1937, Serial No. 67,749

Term of patent 3½ years

To all whom it may concern:

Be it known that I, Joseph J. Kopacka, a citizen of the United States, residing at Greensburg, in the county of Westmoreland and State of Pennsylvania, have invented a new, original, and ornamental Design for a Portable Service Bar, of which the following is a specification, reference being had to the accompanying drawing, forming part thereof.

In the drawing, the figure is a perspective view of a portable service bar, showing my new design.

I claim:

The ornamental design for a portable service bar, as shown.

JOSEPH J. KOPACKA.
